UNITED STATES PATENT OFFICE.

FERDINAND EPHRAIM, OF BODIE, CALIFORNIA.

WATCH-CASE.

SPECIFICATION forming part of Letters Patent No. 233,405, dated October 19, 1880.

Application filed August 9, 1880. (No model.)

To all whom it may concern:

Be it known that I, FERDINAND EPHRAIM, of Bodie, county of Mono, and State of California, have invented a Dust-Protector for 5 Watch-Cases; and I hereby declare the following to be a full, clear, and exact description thereof.

My invention relates to an improved construction of watch-cases by which dust and 10 moisture may be prevented from entering the case and injuring the works of the watch. Much damage is done in a very short time to 15 watches carried by persons engaged in occupations where there is much dust by fine particles of dirt, which get between the cases and gradually reach the operative parts of valuable watches, and in a short time destroy the usefulness of the time-piece.

My invention consists in making the rim to 20 which the cases are hinged so that a groove is formed around the periphery of the cases outside, and this arrests the dirt and prevents it 25 entering the watch.

Referring to the accompanying drawings, 25 Figure 1 is a view of my device. Fig. 2 is an edge view.

A represents the rim of a watch-case. B B' are the outside cases, and C is my dust-cover. This dust-cover is formed of a single strip of

metal secured around the periphery of the rim 30 A in shape of a flat ring or band, and it extends on each side of the rim far enough to cover the crevice between the cases and the rim when the cases are closed, so as to prevent the entrance of dirt or dust when the 35 cases are closed.

In manufacturing watch-cases the part C will form a part of the rim A, the whole being made from solid material; but it will be seen that I can attach the dust-cover to watches 40 now in use by forming a separate band and afterward securing it around the periphery.

Having thus described my invention, what I claim as new, and desire to secure by Letters Patent, is—

A dust-protector for watch-cases consisting of the flat rim or band C, surrounding the rim of the watch and forming flanges which project above the edges of the cases B B', substantially as and for the purpose herein described.

In witness whereof I have hereunto set my hand.

FERDINAND EPHRAIM.
